WASHING MACHINE WITH WATER MOTOR
HAVING AN EXHAUST CONNECTED TO
WASHER TUB

Joseph M. Tyrner, Morristown, N. J.

Application October 8, 1949, Serial No. 120,276

10 Claims. (Cl. 68—53)

1

This invention relates to washing machines of the type that are used in homes and apartments for doing small washings, such as stockings, linens and children's clothes.

One object of the invention is to provide an improved washing machine that can be used with a minimum of attention, the machine being constructed so as to change automatically from washing to rinsing.

Another object is to provide a hydraulically-operated washing machine in which an agitator is rocked to and fro by a simple and reliable mechanism having a water motor from which the exhaust is discharged into the washing tub to supply water for the washing operation, and subsequently for rinsing.

Features of the invention relates to structure that is inexpensive to build and assemble, and that is particularly reliable in use.

Other objects, features and advantages of the invention will appear or be pointed out as the specification proceeds.

In the drawing, forming a part hereof, in which like reference characters indicate corresponding parts in all the views,

Figure 1 is a vertical sectional view through a washing machine embodying this invention,

Figure 2 is a view of the operating mechanism of the machine shown in Fig. 1, the view being taken along the line 2—2 of Fig. 1,

Figure 3 is a sectional view taken on the line 3—3 of Fig. 2,

Figure 4 is a top plan view, of the mechanism shown in Fig. 2, but with the valve housing shown in section along the line 4—4 of Fig. 2,

Figs. 5 and 6 are sectional views taken on the lines 5—5 and 6—6, respectively of Figs. 2 and 5, respectively.

The washing machine includes a generally cylindrical tub 10 which has a partition forming an intermediate bottom 11. The tub has a bottom 12 below the partition 11, the bottom being preferably of one piece construction with the sides of the tub. In the illustrated washing machine, the intermediate bottom is supported by and connected with a corrugation 14 that extends inwardly and circumferentially around the side of the tub 10. A cover 16 fits over the upper end of the tub 10, and closes the tub to prevent water from splashing out when the washing machine is in use.

There is a circle of openings 18 in the intermediate bottom for the passage of water from the chamber beneath the bottom 11 into the washing chamber above the intermediate bot-

2

tom. These openings 18 are located near the wall of the tub 10 and at closely spaced regions around the circle so that water entering the washing chamber from beneath the intermediate bottom 11 is distributed substantially uniformly around the outer portion of the washing chamber and at the lower end of the washing chamber.

The tub 10 is supported by feet 20 having soft pads 21 secured to their bottom faces. There are preferably three such feet angularly spaced by 120° around the under face of the bottom 12 for stably supporting the washing machine along a table or other underlying surface.

15 A drain valve housing 23 is attached to the underside of the tank bottom 12 by bolts 24 extending through the bottom 12. This drain valve housing 23 has openings 25 that register with openings 27 in the tub bottom 12 for draining liquid from the tub. A base 29 extends upward from the drain valve housing 23 into the chamber between the tank bottom 12 and the partition 11.

20 There is an agitator 30 within the washing chamber. This agitator preferably has three blades 32 angularly spaced from one another by 120° and the blades 32 are secured to a sleeve 34 of the agitator. This sleeve 34 has bearings 36 and 37 pressed into its upper and lower ends, respectively. The bearings 36 and 37 are free to turn on an axle 39 which is secured at its lower end to the base 29. The agitator sleeve 34 extends through a central opening 40 in the partition 11 and preferably has a flange 41 substantially filling this central opening so as to reduce the amount of water that can flow through the clearance between the sleeve 34 and the edge of the central opening 40.

25 The agitator axle 39 is a hollow tube and serves as an overflow pipe for the washing chamber, there being ports 43 near the upper end of the agitator axle 39. Water in the tub 10, above the level of the overflow ports 43, flows through these ports into the hollow interior of the agitator axle 39, and downward into the drain valve housing 23.

30 In order to prevent the overflow ports 43 from being clogged by clothes coming up against them, there are guards 44 attached to the upper end of the agitator sleeve 34 and extending upward in front of the overflow ports 43 at angularly spaced regions around the agitator. These guards keep the clothes spaced from the ports 43, and if the openings between the guards 44 are clogged by clothes, they will be freed again 35 by the movement of the guards with the agitator.

There is a water outlet 45 at one end of the drain valve housing 23, and this water outlet 45 has a cylindrical outside surface of a size and shape to fit into a hose through which the water can be drained. If the washing machine is placed in a bath tub or over a wash basin, no hose need be used on the water outlet 45.

A valve 47, in the valve housing 23, is secured to the lower end of a rod 49 which extends upward through the agitator axle 39 to a knob 50. This knob 50 has a lower end portion with a diameter that fits the axle 39 as a bearing; and the knob 50 is threaded over the upper end of the rod 49 so that rotation of the knob in one direction lifts the rod 49, while rotation of the knob 50 in the other direction permits the rod 49 to move downward.

The upward and downward movement of the rod 49 raises and lowers the drain valve 47 so as to move a face covering 52 of the valve into and out of contact with annular valve seats 54 at the lower ends of the openings 26. A portion of the peripheral edge of the drain valve 47 is cut away to straddle the boss of the valve housing 23 through which the bolt 24 extends. This recess in the periphery of the drain valve 47 leaves it free to move up and down parallel to the bolt 24, but prevents the drain valve 47 from rotating and thus prevents turning of the rod 49 when the knob 50 is being rotated to open or close the drain valve 47.

There are openings 56 in the drain valve 47, beneath the agitator axle 39, so that water overflowing into the agitator axle can always escape from the agitator axle 39 into the drain valve housing 23 and from there to the drain outlet 45, regardless of the position of the drain valve 47.

The agitator is oscillated by a gear 60 secured to the lower end of the sleeve 34. This gear 60 meshes with a special gear 62 which is best shown in Fig. 3. This special gear 62 has a segment 63 in mesh with the agitator gear 60; and has another segment 64, of smaller pitch diameter, in mesh with a rack 65 on one side of a piston rod 66.

The piston rod 66 slides in a sleeve 68 extending from one end of a cylinder 69 of a water motor 10. A piston 72 is connected with one end of the piston rod 66 and this piston reciprocates back and forth in the cylinder 69 in response to the admission of water under pressure into alternate ends of the cylinder 69 under the control of a valve which will be described in connection with Figs. 4 and 6.

The piston rod 66 is held against rotation by a stud 74 secured to the sleeve 68 and extending into a longitudinal channel 76 provided in the piston rod 66 on the side opposite to the rack 65.

As the piston rod 66 moves back and forth in accordance with the strokes of the piston 72, the rack 65 oscillates the special gear 62 about an axle 78 and transmits motion through the special gear 62 to the agitator gear 60. The difference in the pitch diameter of the segments 63 and 64 provides a simple and compact mechanism for determining the mechanical advantage of the water motor 10 with respect to the agitator gear 60. It will be evident that the angle through which the agitator oscillates is not the same as the angle through which the special gear oscillates because the pitch diameter of the gear segment 63 is not the same as the pitch diameter of the agitator gear 60.

The water motor 10 has a head-end port 91

and a crank-end port 92. These ports communicate with chambers 91' and 92', respectively, in a valve housing 93 at one side of the water motor 10. The flow of water into and out of the chambers 91' and 92' is determined by a control valve 94 (Fig. 6) which slides in a valve bore 96 at one side of the water motor. Both ends of the valve bore 96 are open for the escape of water into the space surrounding the outside of the water motor.

The mid-portion of the valve bore 96 communicates with a water inlet conduit 98 leading upward from a water supply fitting 100 that has a spout 102 (Fig. 5) to which a hose is connected. This hose is preferably provided with a slip fitting for connecting to the hot water faucet of a bath tub, wash basin or sink from which the washing machine is filled with water.

Referring again to Fig. 6, the valve 94 has 20 collars on it which slide as pistons in the valve bore. When the control valve 94 is in the position shown in Fig. 6, water from the inlet conduit 98 flows into the valve bore 96 and through the chamber 91' to the cylinder port 91. Water pressure is thus exerted against the head-end of the motor piston. Water is free to exhaust from the water motor through the crank-end port 92 and chamber 92' and from this chamber 92' through the open right-hand end of the valve bore 96. This provides for the exhaust of water from the crank-end side of the piston.

Movement of the control valve 94 to the right in Fig. 6 connects the water inlet conduit 98 with the chamber 92' and the cylinder port 92; and 35 puts the cylinder port 91 and chamber 91' in communication with the open left-hand end of the valve bore 96.

The valve operating mechanism for moving the valve 94 is best shown in Fig. 4. A valve operating lever 105 has a hub portion that fits 40 around the upper end of the axle or stud 78, and that is free to oscillate on this axle. The other end of the operating lever 105 is forked and fits over a reduced diameter portion 107 at one end of the control valve 94. There are confronting shoulders 109 and 110 at the left and right-hand ends, respectively, of the reduced diameter portion 107 of the control valve 94.

Two studs 111 and 112 extend upward from the top face of the gear 62. There is a flange 115, best shown in Fig. 5, extending downward from the operating lever 105 into the path of the studs 111 and 112.

When the gear 62 turns to the right in Fig. 4, the stud 111 strikes the flange 115 of the operating lever 105 to move the operating lever to the right. When the gear 62 turns toward the left, the stud 112 strikes the downwardly extending flange 115 of the operating lever 105 and rocks the operating lever to the left. The angular distance between the studs 111 and 112 provides a lost motion connection between the special gear 62 and the operating lever 105. The length of the reduced-diameter portion 107 of the valve 94, in excess of the thickness of the forked end of the lever 105, provides a lost motion connection between the valve 94 and its operating lever 105.

A spring 118 has its opposite ends connected with pins 121 and 122 on the cylinder sleeve 68 and operating lever 105, respectively. The pin 122, which moves as a unit with the operating lever 105, is so located that during the operation of the lever 105 this pin 122 moves from one side to the other of a center line joining the axes of the pin 121 and axle 78. This center line will be

referred to as the line 78-121. With this construction, the force of the compressed spring 118 tends to rock the operating lever 105 to the left when the operating lever is in the position shown in Fig. 4. This same pressure of the spring 118, however, will tend to rock the operating lever 105 to the right when the lever 105 is moved far enough to shift the pin 122 over to the right-hand side of the line 78-121.

In the operation of the device, the water motor 70 turns the special gear 62 toward the right until the stud 111 moves the operating lever 105 far enough to carry the pin 122 beyond the line 78-121. The pressure of the spring 118 then operates to shift the operating lever 105 with a snap action, and the forked end of the operating lever moves over against the shoulder 110 of the control valve 94 and shifts the control valve to the other end of its stroke.

This movement of the control valve reverses the water motor 70 and causes the special gear 62 to turn in the opposite direction until the stud 112 moves the operating lever 105 far enough to shift the pin 122 back to the left-hand side of the line 78-121. As soon as the pin 122 has passed some distance beyond this line, the force of the spring 118 is sufficient to move the operating lever 105 to the left with a snap action. This brings the forked end of the operating lever into contact with the shoulder 109 of the control valve 94 and shifts the control valve to the other end of its stroke to again reverse the water motor.

In the operation of the washing machine, the tub is filled with water and as much soap or soap powder as required for the wash. The motor moves the agitator back and forth to keep the clothes moving in the water, and the hot water from the motor exhaust forces some of the water under the partition 11 to move upward through the openings 18. This clear water mixes with the soapy water around the outside of the washing compartment and raises the level of the water in the tub so that some of the water runs out through the overflow ports 43. The agitator causes a gradual mixing of the soapy water with the clear water that comes up from the openings 18.

The water in the washing compartment is diluted by the introduction of fresh water from under the partition 11 and the draining out of dirty soapy water from the upper center region of the tub through the overflow ports 43. The amount of water exhausted from the motor is so proportioned to the size of the washing compartment that the washing operation is completed before the soapy water in the washing compartment is so much diluted that it no longer has any washing effect.

Continued flow of fresh water from beneath the partition rinses the clothes and the water in the compartment above the partition becomes progressively clearer as the clothes become thoroughly rinsed. The transition from the washing operation to the rinsing operation is progressive, therefore, and requires no intervention by the operator of the washing machine. It is sufficient to merely place the clothes and soap in the washing machine, and then let the washing machine run, with an adequate supply of hot water to the motor, until a predetermined time has elapsed. The water is then shut off, the valve 47 is opened to drain the tub and the clothes are removed from the washing machine for wringing and drying.

The preferred embodiment of the invention has

been illustrated and described, but some features of the invention can be used alone or in different combinations without departing from the invention as defined in the claims.

I claim as my invention:

1. In a washing machine of the class wherein a tub has sides and a bottom, and there is an agitator in the tub connected with a water motor at the bottom of the tub, and the water motor has an exhaust that discharges water from the motor into the tub, the combination with said tub of a partition located in the tub above the water motor and forming an intermediate bottom in the tub, there being at least one opening adjacent to the periphery of the partition for the flow of water into the space above the partition along a zone near the sides of the tub.

2. In a washing machine of the class wherein a tub has sides and a bottom, and an agitator in the tub is driven by a water motor, the combination with said tub of a partition extending across the tub above said bottom and forming an intermediate bottom for the tube, the agitator in the tub being above the intermediate bottom, there being openings through the intermediate bottom for the flow of water into and out of the space above the partition and said openings being adjacent to the sides of the tub so that water entering the tub moves upward in a zone near the sides of the tub, the water motor being located in the space between the bottom and the partition, an exhaust from the motor opening into the space below the partition, and an overflow drain at the upper portion of the tub near the central axis of the tub.

3. In a water power washing machine of the class wherein a tub has sides, a bottom, and an agitator in the tub is driven by a water motor, the combination with said tub of a partition above and spaced from the bottom of the tub, the agitator in the tub being above the partition, and the water motor being located in the space between the bottom and the partition, an exhaust conduit leading from the motor to the space between the bottom and the partition, there being openings near the peripheral portion of the partition for the flow of water toward and from the space above the partition, a drain at the bottom of the tub, and valve means for opening and closing the drain.

4. In a washing machine of the class wherein a tub has sides and a bottom, and an agitator in the tube is driven by a water motor, the combination with said tub of a partition in the tub above the bottom, there being at least one opening near the periphery of the partition for the flow of water into and out of the space above the partition and along a zone near the sides of the tub, the agitator in the tub being above the partition, an exhaust from the water motor opening into the space between the partition and the bottom of the tub, a hollow axle on which the agitator oscillates, said axle being located along a central axis of the tub and having at least one top opening for the overflow of water from the tank, and a water drain communicating with the lower end of the axle.

5. In the washing machine described in claim 4 with a drain at the bottom of the tank, a valve for opening and closing said drain, an actuator for the valve located at the upper end of the agitator axle, and a motion transmitting connection extending from the actuator through the axle to the drain valve.

6. In a washing machine of the class where-

in a tub has a cylindrical side wall and a bottom integral with the lower end of the side wall, and an agitator in the tub is driven by a water motor, the combination with said tub of an inwardly extending peripheral corrugation in the side wall of the tub at a level near the bottom, a partition located within the tub and supported from the inwardly extending corrugation, said partition having a circle of holes near its peripheral edge for the flow of water into and out of the space above the partition along a substantially cylindrical zone near the side wall of the tub, an axle for the agitator rigidly connected with the bottom of the tub and extending upward through the partition to a level near the top of the tub, the agitator being in the tub above the partition, bearings connected with the agitator and fitting the agitator axle, said axle being hollow and having at least one opening near its upper end for the overflow of water from the tub, the water motor being located in the space between the partition and the bottom of the tub, an exhaust from the water motor opening into the tub below the partition, a valve housing connected with the bottom of the tub and having a drain outlet, at least one passage through which water drains from the tub into the valve housing, a valve in the housing for opening and closing the drain conduits, a rod connected with the valve element and extending upward through the agitator axle, and a knob located at the top of the axle and connected with the rod and movable to open and close the drain valve.

7. In a washing machine of the class wherein a tub has an agitator therein, a hollow fixed axle for the agitator extending upward from the bottom of the tub, and a drain outlet comprising at least one opening from the tub into the interior of the hollow axle at the lower end of the tub, the combination with said tub of a valve for opening and closing said outlet, and an operating rod for the valve extending upward through the axle of the agitator.

8. In a washing machine of the class wherein a tub has an agitator therein, an axle extending upward from the bottom of the tub and on which the agitator oscillates, said axle being hollow and having openings at its lower and upper end for the flow of water from the tub, and the tub has a drain outlet at the bottom of the tub, the combination with said tub of a valve for opening and closing the drain outlet, and a valve operating rod extending from the valve upward through the hollow interior of the agitator axle for manually operating the valve.

9. In a washing machine of the class wherein a tub has a bottom with a circle of drain openings through said bottom around a center axis of the tub, and a tubular axle extends upward from the bottom of the tub substantially along the center axis, an agitator that oscillates on the axle as a bearing, said axle having openings at its upper and lower end for the overflow of water from the tub, the combination with said tub of a valve located at the bottom of the tub and extending across the open lower end of the axle and under the drain openings in the bottom of the tub, said valve having a face that is movable into position to block the flow of water from the drain openings, but having a permanently open passage under the axle for flow of water from the axle, a rod secured to the valve and extending upward through the axle, means for preventing the valve from rotating, and an operating knob at the upper end of the axle with threads that engage with other threads on the upper end of the rod, said knob having a surface that rotates on a confronting bearing surface of the agitator axle.

10. In a washing machine of the class wherein a tub has an axle rigidly connected therewith, and, an agitator oscillates in the tub, the combination with said agitator of an axle which is hollow and has at least one opening at its upper end for the overflow of liquid from the tub, and guards in front of said one or more openings for preventing clothes in the tub from blocking the overflow of water into the axle, said guards being connected with the agitator and movable as a unit with the agitator so as to cause movement of any clothes that come into contact with said guards.

JOSEPH M. TYRNER.
